(57) **CLAIM**

The ornamental design for a wheel rim trim, as shown and described.

DESCRIPTION

FIG. 1 is a front perspective view of a wheel rim trim.

FIG. 2 is a rear perspective view of the trim shown in FIG. 1.
FIG. 3 is a front perspective view of the trim disposed in a linear fashion.

FIG. 4 is a front view of the trim shown in FIG. 3.

FIG. 5 is a rear view of the trim shown in FIG. 3.

FIG. 6 is a top plan view of the trim shown in FIG. 3.

FIG. 7 is a bottom plan view of the trim shown in FIG. 3.
FIG. 8 is a right side elevational view of the trim shown in FIG. 3.

FIG. 9 is a left side elevational view of the trim shown in FIG. 3; and,

FIG. 10 is an environmental cross-sectional view of the trim shown in elevational.

The wheel rim trim is shown broken away in FIGS. 3-7 for ease of illustration.

The broken line shown in FIG. 10 forms no part of the claimed design.
